(57) CLAIM

The ornamental design for a soap dispenser, as shown and described.

DESCRIPTION

FIG. 1 is a front plan view showing one embodiment of the new design for a soap dispenser;

FIG. 2 is a side plan view from one side of the soap dispenser of FIG. 1;

FIG. 3 is a side plan view of the other side of the soap dispenser of FIG. 1;

FIG. 4 is a top plan view of the soap dispenser of FIG. 1;

FIG. 5 is a bottom plan view of the soap dispenser of FIG. 1;

FIG. 6 is a side perspective view of the soap dispenser of FIG. 1; and,

FIG. 7 shows the soap dispenser of FIG. 1 in an opened position, prior to receiving soap or a soap-containing bag.

The broken-line disclosure in the views is understood to represent portions of the soap dispenser in which the design is embodied, but which form no part of the claimed design.
